UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

MEANS FOR MOUNTING ELECTRIC GENERATORS AND THE LIKE ON MOTOR-VEHICLES.

1,178,718.

Specification of Letters Patent. Patented Apr. 11, 1916.

Application filed August 7, 1914. Serial No. 855,692.

To all whom it may concern:

Be it known that I, EDWARD A. HALBLEIB, a citizen of the United States, and resident of Rochester, in the county of Monroe and State of New York, have invented certain new and useful Improvements in Means for Mounting Electric Generators and the like on Motor-Vehicles, of which the following is a specification.

- 10 This invention relates to means by which an electric generator, motor, or the like, particularly one which is employed for the purpose of electric lighting or of starting an engine, may be mounted upon a motor-
15 vehicle in a position between the forwardly projecting ends of the side frame-members of the vehicle, where the generator may be conveniently connected with the forward end of the crank-shaft of the engine.
20 One object of the invention is to produce means, for the purpose in question, which shall be simple in construction, and strong and rigid, but which shall be readily adjustable to accommodate them to the various dimensions and forms of the vehicle-frames upon which the generator or the like may be mounted.

To this end the invention comprises a cranked or offset cross-bar, together with means for securing its ends to the frame-members of the vehicle and its middle portion to the generator or other device, or to a base or support upon which such device is carried, the connections between the cross-bar and the other parts being rotatable, so that by swinging the bar to various angular positions it may be accommodated to the various forms and positions of the frame-members.

40 Other objects and features of the invention will be set forth hereinafter in connection with the following description of the preferred embodiment of the invention.

In the accompanying drawings:

- 45 Figure 1 is a perspective view of a construction embodying the present invention, as applied to a motor-vehicle of ordinary form; and Fig. 2 is a side-elevation of the same.
50 The invention is illustrated as embodied in a construction comprising a base 5, upon which a generator or other device may be carried, this base being mounted and supported between the front ends of the side

frame-members 6 of a motor-vehicle, in front of the radiator 7 thereof, the driving-connection between the generator and the engine being provided by a rearwardly-projecting shaft 8, extending below the base 5 from a gear-box 9 carried thereby. The rear end of the shaft 8 is coupled to the forward end 10 of the crank-shaft of the engine. In such an arrangement it is essential that the shaft 8 be substantially in alignment with the crank-shaft 10, and accordingly it is important that the base 5 be supported in a substantially horizontal position at an exactly determined elevation.

The present invention resides particularly in the means for connecting the forward end of the base 5 with the downwardly-curved ends of the frame-member 6. For this purpose a cross-bar 11 is employed, this bar being cranked or bent, between its end-portions and its middle-portion, so as to provide a straight middle-portion 12, and two straight end-portions 13 which are in alignment with each other and parallel with the middle-portion.

The end-portions 13 are mounted in concave seats in two seat-blocks 14, and the lower surfaces of these blocks are concave so as to seat firmly upon the convex upper surfaces of the frame-members 6. To hold the cross-bar and the seat-blocks in place, two clips 15 span each end of the cross-bar on opposite sides of the corresponding frame-member, these clips being adjustable to the various depths or thickness of the frame-members in connection with which they may be employed, and being adapted to clamp the parts all securely together. After the position of the seat-blocks on the frame-members has been determined they may be fixed, against longitudinal sliding movement, by means of dowels 16 seated in perforations in the seat-blocks and the frame-members.

The middle-portion of the cross-bar is secured to the base 5 by means of clamps 17, which are screwed to the base and clasp the bar. It will be apparent that the connections between the cross-bar and the base 5, and also the connections between the cross-bar and the side frame-members, permit rotative or angular movement of the cross-bar when the fastening-devices are loosened, such rotation being permissible through an

entire circle, as indicated by a broken line 18 in Fig. 2. It will also be apparent that the means by which the cross-bar is clamped to the frame-members may be located at various distances from the forward ends of these frame-members. Accordingly, by the use of these two adjusting movements the parts may be adjusted to support the forward end of the base 5 at the required level, whatever the height or the amount of downward or upward curvature of the frame-members, so that the apparatus can be readily adapted to any motor-vehicle of ordinary construction, having a frame of the type in question.

Various means may be employed for supporting the rear end of the base 5, but it is shown in the drawings as carried by an angle-iron cross-bar 19, of which the ends 20 are fixed to the side frame-members by lugs and bolts 20.

In addition to performing the function of clamping the cross-bar 11 to the base 5, the clamps 17 are upwardly elongated and 25 perforated, to adapt them to support the license-plate 22 usually carried at the front of a motor-vehicle. In this manner I provide not only for the convenient and secure support of this license-plate, but the arrangement has the further advantage that the plate partly conceals the apparatus behind it, thus conducing to neatness in the appearance of the vehicle.

I claim:—

35 1. Means, for the purpose described, comprising a cross-bar cranked to provide an offset middle-portion, and clamps for securing the middle-portion of the bar to a dynamo or the like, and the ends of the bar 40 to the frame-members of a motor-vehicle, said clamps being rotatably connected with the bar to permit the latter to be used in various angular positions.

2. In combination with the side frame-members of a motor-vehicle, a cross-bar cranked to offset its middle-portion and con-

nected, at its ends, to said frame-members, and a dynamo-base fixed at its inner end to the frame of the vehicle and having, at its outer end, a clamp embracing the middle-portion of the cross-bar.

3. In combination with the side frame-members of a motor-vehicle, a cross-bar cranked to offset its middle-portion and connected, at its ends, to said frame-members, and a dynamo-base fixed at its inner end to the frame of the vehicle and having, at its outer end, a clamp embracing the middle-portion of the cross-bar, and an arm extending upwardly from said clamp and adapted to support a number-plate.

4. Means, for the purpose described, comprising blocks with concave lower surfaces adapted to seat upon the side frame-members of a motor-vehicle, and with concave 65 seats in their upper surfaces; a cross-bar supported, at its ends, in said seats; clips for connecting the cross-bar with said frame-members to clamp the cross-bar and the blocks in place thereon; and means for 70 connecting a dynamo or the like with the middle-portion of the cross-bar.

5. In combination with the side frame-members of a motor-vehicle, and a dynamo or the like located between the ends of the 75 frame-members; a cross-bar; clamps, for securing the ends of the cross-bar to the frame-members, adjustable along the frame-members to vary the height of their points of attachment thereto; and means for 80 securing the dynamo to the middle-portion of the cross-bar, said means permitting relative movement of the cross-bar and the dynamo to compensate for said movement of the clamps along the frame-members without 85 longitudinal movement of the dynamo.

In testimony whereof, I affix my signature in presence of two witnesses.

EDWARD A. HALBLEIB.
